(57) **CLAIM**

We claim the ornamental design for a connector for a power transmission and communications system, as shown and described.

DESCRIPTION

FIG. 1 is a rear view of a connector for a power transmission and communications system showing our new design.

FIG. 2 is a rear perspective view of the connector for the power transmission and communications system.

FIG. 3 is a front view of the connector for the power transmission and communications system.

FIG. 4 is a front perspective view of the connector for the power transmission and communications system.

FIG. 5 is a top view of the connector for the power transmission and communications system.

FIG. 6 is a right side view of the connector for the power transmission and communications system.

FIG. 7 is a left side view of the connector for the power transmission and communications system; and,

FIG. 8 is a bottom view of the connector for the power transmission and communications system.

The broken line showing is included for the purpose of illustrating portions of the "article" and forms no part of the claimed design.
